UNITED STATES PATENT OFFICE.

FREDERICK W. HANKS, OF CLEVELAND, OHIO.

WATER-METER.

1,192,189.

Specification of Letters Patent. Patented July 25, 1916.

Application filed August 28, 1914. Serial No. 859,086.

To all whom it may concern:

Be it known that I, FREDERICK W. HANKS, a citizen of the United States, and a resident of Cleveland, county of Cuyahoga, and State of Ohio, have invented a new and useful Improvement in Water-Meters, of which the following is a specification, the principle of the invention being herein explained and the best mode in which I have contemplated applying that principle, so as to distinguish it from other inventions.

The object of the present invention is to provide a water meter smoothly and accurately operable under various conditions of use.

Among the particular objects of the invention are the provision of a meter which is simple in construction, and whose parts may be economically manufactured and easily assembled or dismantled; the provision of simplified and improved means or operatively communicating motion of the measuring valve to the registering mechanism; the provision of improved means for mounting the valve; and the provision of an improved valve.

To the accomplishment of the foregoing and related ends, said invention then consists of the means hereinafter fully described and particularly pointed out in the claims.

The annexed drawing and the following description set forth in detail, certain mechanism embodying the invention, such disclosed means constituting, however, but one of various mechanical forms in which the principle of the invention may be used.

In said annexed drawing:—Figure 1 is a central sectional view of a meter embodying the invention; Fig. 2 is a plan view on the line 2—2 in Fig. 1, with the top cover and certain operative parts removed; Fig. 3 is a sectional view on the line 3—3 in Fig. 1; and Fig. 4 is a broken sectional view of a preferred form of valve.

The meter comprises a casing section 1, formed with an inlet opening 2 and with an outlet opening 3, the bottom of the central portion of the casing having the form of a cone 4. A partition 5 is removably seated in the casing 1, over the conical bottom 4, and is held in place by a cover 6, which is secured to the casing section 1, preferably by screws 7. The cover 6 carries any suitable registering or recording mechanism 8, illustrated diagrammatically in the draw-

ing, the registering or recording mechanism being operable by rotation of an arm 9.

The partition 5 is formed with a port 10, from which a duct leads downwardly, the duct being formed by a wall 11, separating the port from the outlet passage 3, and by a foraminous wall 12, whose apertures open into the measuring chamber that is formed between the bottom of the casing section 1, and the partition 5.

A casing 13, is mounted on the partition 5, and it carries a tappet wheel 14 rotatable on a pin 15, having an enlarged head 16, with a beveled edge disposed within the casing 13. A pin 17 is rotatably mounted in

the casing 13, and carries any desirable number of tappets 18, which engage the tappet wheel 14, and the pin also carries a tappet wheel 19. Mounted fixedly on the apex of the conical bottom 4 of the casing section 1, is a spherical bearing 20, which is formed of self-lubricating, substantially non-expansive material.

I prefer to use either mica or graphite, or a mixture of mica and graphite for forming the bearing. A conical valve 21 is mounted on the bearing 20, and it carries a tappet 22 engaging the tappet wheel 19.

The valve 21 is formed, as illustrated in Fig. 4, by two outer layers of metal, 24 and 25, between which is inclosed a central layer 26 of compressible material, the compressible material extending beyond the inclosing metal layers at the edge of the valve. I prefer to construct the valve of a central layer of cork inclosed by outer layers of brass.

In operation, the water flows in through the inlet opening 2, and upwardly through an opening 23, into the space between the partition and the cover, and thence downwardly through the port in the partition whence it is discharged through the foraminous wall of the duct extending from the port against the upper surface of the valve. The flow of water discharged against the valve, causes the valve to gyrate, and as it does so, the water flows around its upper surface and out through the discharge opening 3. In order to permit the gyroscopic motion of the valve, the latter is slotted to embrace the walls of the duct 10. The gyroscopic motion of the valve is frictionless as possible because the bearing upon which it is mounted is formed by self-lubricating mate-

rial, and its movement will be substantially unaffected by variation in the temperature of the water passing through the meter, because the bearing is formed of substantially non-expansible material, and also because the valve itself is formed with a central layer of compressible material. Any material escape of water around the valve is prevented because the central layer of compressible material makes intimate contact with the wall of the measuring chamber, and yet the contact is yielding so that substantially no friction is produced. Gyratory motion of the valve produces rotary motion of the tappet 22, and this motion is communicated to the registering or recording mechanism by the tappet wheels 19, the tappets 18 and the tappet wheel 14. By means of this series of tappet wheels and tappets, a highly effective reduction between the motion of the valve and that of the registering or recording mechanism is secured in a very simple manner.

Other modes of applying the principle of my invention may be employed instead of the one explained, change being made as regards the mechanism herein disclosed, provided the means stated by any of the following claims or the equivalent of such stated means be employed.

I therefore particularly point out and distinctly claim as my invention:—

1. In a water meter, the combination of a casing having a conical bottom; a ported partition in the casing forming a measuring chamber between itself and the bottom; an inlet passage extending above the partition, and communicating through the port thereof with the measuring chamber; an outlet passage extending from the measuring chamber; and a gyratory conical valve mounted on the bottom of the casing.

2. In a water meter, the combination of a casing having a conical bottom; a ported partition in the casing forming a measuring chamber between itself and the bottom; an inlet passage extending above the partition, and communicating through the port thereof

with the measuring chamber; an outlet passage extending from the measuring chamber; a duct extending downwardly from the port and formed with a wall separating it from the outlet passage and with a foraminous wall facing the measuring chamber; and a gyratory conical valve mounted on the bottom of the casing.

3. In a water meter, the combination of a casing section having a conical bottom; a ported partition removably seated on the section and forming a measuring chamber between itself and the bottom; a cover removably secured to the section; an inlet passage extending to the space between the partition and the cover; an outlet passage extending from the measuring chamber; and a gyratory conical valve mounted on the bottom of the section.

4. In a water meter, the combination of a casing; a convex spherical bearing formed of self-lubricating material mounted therein; and a gyratory valve having a concave spherical portion mounted on the bearing.

5. In a water meter, the combination of a casing; a convex spherical bearing formed of self-lubricating, substantially non-expansible material mounted therein; and a gyratory valve having a concave spherical portion mounted on the bearing.

6. In a water meter, the combination of a casing; a spherical bearing formed of self-lubricating material mounted therein; and a gyratory valve mounted on the bearing, the valve being formed by outer layers of metal and a central layer of compressible material extending beyond the layers of metal at the edge of the valve.

7. In a water meter, a gyratory valve comprising outer layers of metal, and a central layer of cork extending beyond the layers of metal at the edge of the valve.

Signed by me, this 26th day of August, 1914.

FREDERICK W. HANKS.
